UNITED STATES PATENT OFFICE.

EDWARD G. WEILER, OF CLEVELAND, OHIO, ASSIGNOR TO THE ELECTRIC VULCANIZING RUBBER COMPANY, OF CLEVELAND, OHIO, A CORPORATION OF OHIO.

DESIGN FOR A TIRE.

59,049.

Specification for Design. Patented Sept. 13, 1921.

Application filed February 17, 1921. Serial No. 445,899. Term of patent 14 years.

To all whom it may concern:

Be it known that I, EDWARD G. WEILER, a citizen of the United States, residing at Cleveland, in the county of Cuyahoga, State of Ohio, have invented a new, original, and ornamental Design for a Tire, of which the following is a specification, reference being had to the accompanying drawing, forming a part thereof.

Figure 1 is a top plan view of a portion of the tire casing; and
Fig. 2 is a transverse section thereof.

I claim:
The ornamental design for a tire as shown.

EDWARD G. WEILER.
